(57) **CLAIM**

The ornamental design for a display screen as shown and described.

DESCRIPTION

FIG. 1 is a front, right, top perspective view of a display screen, showing our new design in a first configuration in which the display screen is flat;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is another front, right, top perspective view of the display screen of FIGS. 1-7 in a second configuration in which the display screen is curved;

FIG. 9 is a front view thereof;

FIG. 10 is a rear view thereof;

FIG. 11 is a left side view thereof;

FIG. 12 is a right side view thereof;

FIG. 13 is a top plan view thereof;

FIG. 14 is a bottom plan view thereof;

FIG. 15 is an enlarged view of portion "15" of FIG. 3;

FIG. 16 is an enlarged view of portion "16" of FIG. 6;

FIG. 17 is an enlarged view of portion "17" of FIG. 6; and,

FIG. 18 is an enlarged view of portion "18" of FIG. 6.

The even-dash broken lines depict portions of the display screen that form no part of the claimed design. The dot-dot-dash broken lines in the drawings represent the extents of the enlarged detail views and form no part of the claimed design.
